H. O. VICTOR

COMBINATION RADIO CABINET AND LOUD SPEAKER

Filed Oct. 14, 1924

Inventor,

Henry O Victor,
By Frank S. Appelman,

Attorney

Patented Dec. 9, 1924.

UNITED STATES PATENT OFFICE.

HENRY O. VICTOR, OF SAGINAW, MICHIGAN.

DESIGN FOR A COMBINATION RADIO CABINET AND LOUD SPEAKER.

Application filed October 14, 1924. Serial No. 11,069. Term of patent 3½ years.

To all whom it may concern:

Be it known that I, HENRY O. VICTOR, a citizen of the United States of America, residing at Saginaw, in the county of Saginaw and State of Michigan, have invented a new, original, and ornamental Design for Combination Radio Cabinet and Loud Speaker, of which the following is a specification, reference being had to the accompanying drawing, forming part thereof.

The figure is a perspective view of a combination radio cabinet and loud speaker, showing my new design.

I claim:

The ornamental design for a combination radio cabinet and loud speaker, as shown.

HENRY O. VICTOR.
